UNITED STATES PATENT OFFICE.

EDWARD FRITSCH, OF MINONK, ILLINOIS.

RAILROAD-TIE.

1,081,666.

Specification of Letters Patent. Patented Dec. 16, 1913.

Application filed April 16, 1913. Serial No. 761,594.

To all whom it may concern:

Be it known that I, EDWARD FRITSCH, a citizen of the United States, residing at Minonk, in the county of Woodford and 5 State of Illinois, have invented certain new and useful Improvements in Railroad-Ties; and I do hereby declare the following to be a full, clear, and exact description of the invention, such as will enable others 10 skilled in the art to which it appertains to make and use the same.

This invention relates to new and useful improvements in railway ties and more particularly that class of ties which may be 15 made of metal, or similar substance, and which will eliminate the necessity of the use of wood in the manufacture of such ties.

The object of my invention is to provide 20 a tie which will have a sure and positive fastening means for the rails whereby the same may be placed thereon and removed therefrom in a simple and effective manner when it is so desired, but will eliminate the 25 danger of the rails becoming loosened from ordinary use or by accident.

Another object of my invention is to provide 30 a tie of the above character which will more firmly hold the rails in place without the use of spikes or similar fastenings as are generally used in the laying of rails in the ordinary construction of railways.

A still further object of my invention is 35 to provide a fastening device wherein any strain on the bolt will be substantially eliminated.

With the above and other objects in view, I will now proceed to describe my invention in the following specification and accompanying drawings, in which,

40 Figure 1 is a view of my improved railway tie, showing the rails applied, one portion being in section; Fig. 2 is a top plan view of my improved tie as it would appear with the rails in place; and Fig. 3 is a detail sectional view taken on line 3—3 of Fig. 1.

45 Referring to the drawings by characters of reference, 5 and 6 indicate railway rails of the usual type comprising the usual head, the web 7, and the flanges 8.

50 The tie preferably comprises a body por-

tion 9, having adjacent each end a recess, in which the flange of the rail is adapted to be received. An overlying tongue 10 is formed adjacent said recess and integral with the tie, and is adapted to overlie a portion of 55 the flange 8 of the rail and hold the same firmly in place. The recess is extended, as clearly illustrated in Fig. 1, and adapted to receive the block 11, having formed at one extremity thereof the overlying tongue 12 60 which is adapted to overlie the flange of the rail opposite the flange which extends beneath the tongue 10. This block 11 is provided intermediate its sides and ends with an aperture, which is adapted to receive 65 a bolt 13, having at its lower extremity a head 14 and being provided at its upper extremity with a nut 15. Extending longitudinally of the recess in the tie, I preferably provide grooves 16 which are adapted 70 to receive the ribs 17, formed integrally with the block 11 when the said block is in place, and it will be clearly seen that when the said block is in place the ribs 17 will extend into the recesses and prevent the block from 75 sliding laterally with relation to the tie. The bolt 13, as is illustrated in Fig. 1, passes upwardly through an opening which registers with the opening formed in the block 11, so that said bolt will firmly clamp the 80 block 11 in place on the tie, and when the apertures in both the block and the tie are in registration the rib 17 will be seated in the grooves 16, as clearly illustrated in Fig. 3. 85

While in the foregoing I have shown and described the preferred embodiment of my invention, I wish it to be understood that I may change the specific arrangements of parts without in any way departing from 90 the spirit and scope of my invention.

Having thus fully described my invention, what I claim is:

A rail tie comprising a body portion having transversely extending recesses adjacent each end, tongues formed integrally with said body portion and overlying a portion of the recesses, said recesses having two spaced V-shaped depressions extending transversely thereof, blocks removably se- 100

cured in the recesses, said blocks having tongues formed along one edge, two spaced ribs formed on the bottom of each of the blocks, said ribs being adapted to coöperate with the V-shaped depressions in the bottom of the recesses and hold the blocks from longitudinal displacement, and bolts adapted to extend through apertures between the V-

shaped depressions and the ribs, whereby the blocks are held firmly in position on the tie. 10

In testimony whereof I affix my signature in presence of two witnesses.

EDWARD FRITSCH.
